DESIGN FOR A STEAM COOKER

Kurt L. Seelbach, Cleveland, Ohio

Application June 2, 1939, Serial No. 85,310

Term of patent 14 years

To all whom it may concern:

Be it known that I, Kurt L. Seelbach, a citizen of the United States, residing at Cleveland, in the county of Cuyahoga and State of Ohio, have invented a new, original, and ornamental Design for a Steam Cooker, of which the following is a specification, reference being had to the accompanying drawing, forming part thereof.

In the drawing:

Fig. 1 is a front elevational view of a steam cooker embodying my new design;

Fig. 2 is a perspective view shown upon a somewhat enlarged scale of the design illustrated in Fig. 1;

Fig. 3 is a side elevational view of the steam cooker; and

Fig. 4 is a plan view of my design.

I claim:

The ornamental design for a steam cooker, substantially as shown.

KURT L. SEELBACH.
